POTENTIOMETER

Morris Nirenberg, Queens, and Michael Sekerich, Brooklyn, N.Y., assignors to Vogue Instrument Corporation, Brooklyn, N.Y., a corporation of New York

Filed July 18, 1961, Ser. No. 124,913

11 Claims. (Cl. 338—144)

The present invention relates generally to variable electrical resistance structures, and in particular to an infinite resolution wire wound potentiometer.

Potentiometers are available on the market which comprise a non-metallic cylindrical wire form which has its outer surface formed with a continuous helical groove having mounted therein a helically wound resistance wire. The opposite ends of the resistance wire are electrically connected to appropriate terminals and a movable electrical contact is made to successive portions of the resistance wire by a wiper arranged contiguous to the outer surface of the wire form. The wiper underlies and engages the resistance wire and is rotatably mounted, as by being connected directly to a control shaft. Accordingly, the wiper may be rotated into various adjusted positions wherein successive portions of the resistance wire are lifted out of the helical groove and provide an adjustable and stepless output as a function of the adjusted position of the wiper.

Potentiometers of this type, which are particularly suited for use in servo mechanisms, should have a number of essential characteristics including, without limitation, the provision of a truly stepless output, a virtually linear output, and a relatively low order of inductance and capacitance to facilitate use in alternating current circuits. Additionally, and in operation, it is important that the potentiometer produce low noise, be capable of operation at relatively low torque, and have a long life despite the wear incident to the continuous adjustment of the potentiometer and the sliding contact between the wiper and the resistance wire.

Broadly, it is an object of the present invention to provide an improved wire wound potentiometer of the infinite resolution type which is capable of realizing one or more of the aforesaid objectives. Specifically, it is within the contemplation of the present invention to provide an improved mounting and controlling arrangement for the wiper or brush of a potentiometer such that the wiper will exactly follow the helical path of the resistance wire, thus minimizing sliding or helical error between the wiper and the resistance wire and insuring extremely long wire life, true stepless output, high accuracy and a relatively low order of electrical noise.

In accordance with an illustrative embodiment demonstrating objects and features of the present invention, there is provided an infinite resolution potentiometer which comprises a mounting plate, a cylindrical wire form of an insulating material projecting from the mounting plate and having an outer surface formed with a continuous helical groove, and a helically wound resistance wire mounted within the groove. Preferably, the wire form is fabricated of a material of good dimensional stability and a low thermal coefficient of linear expansion, resulting in extremely high insulation resistance, low inductance and low capacitance for use in alternating current applications. A lead screw is secured to the mounting plate and projects within and along the longitudinal axis of the wire form and carries a follower in threaded engagement therewith. A wiper is arranged contiguous to the outer surface of the wire form and has a contact section underlying and engaging the resistance wire. The wiper is mounted on the follower for movement along a helical adjustment path coextensive with the resistance

2

wire. Control means are operatively connected to the follower for rotating the follower on the lead screw to move the wiper along the adjustment path. The control means includes a control shaft journalled in the mounting plate and extending coaxially of and through the lead screw and means coupling the control shaft to the follower. The potentiometer is completed by the provision of terminal means electrically connected to the opposite ends of the resistance wire and a collector electrically and rotatably connected to the wiper for providing an appropriate tapoff. The lead screw and follower may be machined to an exceptionally high order of accuracy and with the same pitch as the helically wound resistance wire to assure that the wiper or brush will follow the exact helical path of the resistance wire, with substantially no sliding or helical error.

The above brief description, as well as further objects, features and advantages of the present invention will be more fully appreciated by reference to the following detailed description of presently preferred, but nonetheless illustrative embodiments in accordance with the present invention, when taken in conjunction with the accompanying drawings, wherein:

FIG. 1 is an elevational view of an infinite resolution potentiometer demonstrating features of the present invention, with the cylindrical case or cover sectioned to reveal the contents thereof;

FIG. 2 is an elevational view taken from the right of FIG. 1, with the case or cover sectioned and with parts broken away;

FIG. 3 is a sectional view taken substantially along the lines 3—3 of FIG. 1 and looking in the direction of the arrows;

FIG. 4 is a sectional view taken substantially along the lines 4—4 of FIG. 3, looking in the direction of the arrows and with a portion of the case broken away;

FIG. 5 is a sectional view taken substantially along the lines of 5—5 of FIG. 4 and looking in the direction of the arrows; and

FIG. 6 is a sectional view similar to FIG. 3 but showing a modification in the collector for electrically connecting the rotatable and longitudinally movable wiper to an appropriate terminal.

Referring now specifically to the drawings, there is shown in FIGS. 1 to 5 inclusive a potentiometer 10 which illustrates features of the present invention and includes a housing 12 having a mounting or base plate 14 and a removable cylindrical case or cover 16. The mounting or base plate 14 is appropriately dimensioned and shaped for mounting in an environment structure and is formed in a marginal seat 14a which receives the adjacent end of the removable case or cover 16. In a typical construction, both the mounting plate 14 and the cover 16 may be fabricated of anodized aluminum or similar light weight material.

Projecting from the mounting plate 14 internally of the case 16 is a cylindrical wire form 18 which is fabricated of an appropriate non-metallic material having good dimensional stability and a low thermal coefficient of linear expansion, such as a fluoro-carbon. The outer periphery or surface of the cylindrical wire form 18 is provided with a continuous helical groove 20, shown here for the purposes of illustration on a greatly exaggerated scale. The helical groove 20, which is precision ground and is of generally V-shaped section (see FIG. 3), receives a helically wound resistance wire 22 which may be fabricated of a hard drawn chrome-nickel alloy. The depth of the helical groove 20 is sufficient to accommodate the resistance wire 22 within the confines of the groove (see FIGS. 3 to 5 inclusive). Although only one groove cross section has been illustrated, it will be appreciated that other

groove cross sections will be suitable for accommodating the resistance wire.

The cylindrical wire form 18 is mounted within the case 16 by the provision of an annular retaining flange 14b on the mounting plate 14 (see FIGS. 3 and 4) which has an outer diameter substantially equal to the inner diameter of the wire form 18. The wire form 18 is fitted over the annular retaining flange 14b and is secured to the mounting plate 14 coaxially thereof by the provision of one or more mounting bolts 24 (see FIGS. 4 and 5) which extend lengthwise through the wire form 18 and are threaded into appropriately tapped holes 14c formed in the adjacent end of the mounting plate 14 at locations spaced radially outwardly of the retaining flange 14b.

The mounting plate 14 supports a stationary hollow lead screw 26 which projects within and along the longitudinal axis of the wire form 18. Specifically, and as seen best in FIG. 3, the stationary lead screw 26 includes an integral lead screw mounting section 26a and a threaded section 26b. The mounting section 26a has an outer diameter substantially equal to the inner diameter of the annular retaining flange 14b such that the mounting section 26a may be oriented to have threaded section 26b project axially of the wire form 18. The mounting section 26a is secured to the mounting plate 14 within the annular retaining flange 14b by a number of mounting bolts 28. The threaded or lead screw section 26b is formed with a through bore 26c and projects beyond the wire form 18, for a purpose to be subsequently described.

The threaded section 26b of the lead screw 26 carries a follower assembly 30 which includes a follower nut 32 in threaded engagement with the lead screw section 26b, an insulating block 34 secured to the follower nut 32, a substantially L-shaped mounting arm 36 of electrically conductive material secured to the insulating block 34, and a wiper or brush 38 secured to the mounting arm 36. The wiper or brush 38 extends generally parallel to the longitudinal axis of the wire form 18 and terminates in a contact section 38a which underlies and engages successive portions of the resistance wire 22.

As will subsequently be described, the follower assembly 30 is rotated about and along the lead screw 26 to move the wiper or brush 38 along a helical adjustment path coextensive with the resistance wire 22 such that the transverse segment of the contact section 38a underlying the resistance wire 22 may make continuous contact with successive portions of the resistance wire 22. The transverse segment of the contact section 38a underlying the resistance wire 22 may be slightly grooved or notched to preclude sidewise displacement between the contact and the resistance wire. However, it will be appreciated that the provision of such groove or notch is optional since the pitch of the lead screw section 26b and the pitch of the helical groove 20 is the same and may be held to extremely close tolerances due to the precision grinding or cutting of the lead screw and of the wire groove. In a typical assembly, the wiper or brush 38 is fabricated of a resilient alloy, such as beryllium-copper and is formed with a reduced neck 38b intermediate the contact section 38a and the mounting arm 36 to allow the contact section 38a to flex. The contact section 38a is bowed on an arc corresponding to the outer periphery of the wire form 18 such as not to present any sharp discontinuity to the resistance wire 22 as the contact section moves therebeneath. The contact section 38a may be of precious metal, such as a platinum alloy.

A control assembly or mechanism is operatively connected to the follower nut 32 for rotating the follower nut 32 on the lead screw 26 to move the contact section 38a of the wiper or brush 38 along the adjustment path in electrical contact with the resistance wire 22. The control assembly or mechanism includes a control shaft 40 which has a mounting section 40a extending through a centrally disposed and axially extending bore 14d in the mounting plate 14 and a reduced diameter control section 40b which

extends through the bore of the lead screw 26 and terminates at a location spaced beyond the free end thereof. The mounting section 40a of the control shaft 40 is journalled within the mounting plate 14 by the provision of two precision bearings 42, 44 which have their outer races secured to the mounting plate 14 and have their inner races secured to the mounting section 40a, with the control shaft 40 being held against endwise play by appropriate washers or stops 46, 48.

The control section 40b carries a crosshead 50 which is secured to the control section 40b of the control shaft 40 in any appropriate fashion, as by the pin 52 (see FIG. 3). The cross head 50 in turn carries a pair of spaced and parallel drive fingers 54, 56 which project from the cross head 50 towards the follower nut 32 at opposite side of and equally spaced from the control shaft 40. The drive fingers 54, 56 are slidably engaged in diametrically opposed cutouts 32a, 32b (see FIG. 5) formed in the follower nut 32. In response to rotation of the control shaft 40, the crosshead 50 and drive fingers 54, 56 will rotate and cause the follower nut 32 to move along the threaded section 26b of the lead screw 26, with the follower nut 32 sliding relative to the drive fingers 54, 56.

Collector means are electrically and rotatably connected to the wiper 38 for providing a tap-off and stepless output. In this illustrative embodiment, the collector means includes a collector cylinder 58 which is fabricated of an appropriate precious metal and is mounted coaxially of and within the wire form 18, as seen best in FIGS. 2 to 5 inclusive. The collector cylinder 58 is of sufficient longitudinal extent to be engaged by movable contacts or brushes 60 which are electrically connected to the wiper mounting arm 36 and supported thereon in engagement with the inner peripheral surface of the collector cylinder 58. The movable contacts 60 are fabricated of any appropriate springy material which biases the same into contact with the collector cylinder 58, with the contact 60 moving along a helical contact path in response to rotation of the follower nut 32 on the lead screw 26. The stepless output is made available at a tapoff lead 62 which is electrically connected to the collector cylinder 58 and extended through a cutout 18a and the wire form 18.

Terminal connections are provided to the opposite ends of the resistance wire 22 in any appropriate fashion. In this illustrative embodiment, two terminal strips 64, 66 are mounted longitudinally of and within the wire form 18 (see FIGS. 1 and 3) at locations radially inwardly of the outer periphery of the wire form. The terminal strip 64 has an electrical connection to the end of the resistance wire 22 contiguous to the mounting plate 14, and to a terminal lead 68, while the terminal strip 66 has an electrical connection to the end of the resistance wire 22 remote from the mounting plate 14 and an electrical connection to a terminal lead 70.

Mechanical end stops are provided to limit the traverse of the follower nut 32 on the lead screw 26 and the corresponding traverse of the wiper or brush 38 along the resistance wire 22. In this illustrative embodiment, the follower nut 32 is provided with movable stop pins 72, 74 projecting from the opposite face thereof. The stop pin 72 limits the travel of the follower nut to the right in FIGS. 3 and 4 while the stop pin 74 limits the travel of the follower nut to the left in FIGS. 3 and 4. Specifically, the stop pin 72 cooperates with an adjustable end stop 76 which is secured to the stationary lead screw section 26b adjacent the free end thereof inwardly of the cross head 50. The end stop 76 carries a stationary stop pin 78 which is radially spaced from the longitudinal axis of the lead screw 26 to be contacted by the movable stop pin 72. The end stop 76 is bifurcated and provided with opposed ears 76a, 76b (see FIG. 2) which ears are traversed by an adjustment and locking screw 80 which enables the release and securement of the end stop 76 in any adjusted position on the lead screw sec-

tion 26b. Traverse of the follower nut 32 in the opposite direction and towards the mounting plate 14 is limited by contact of the movable stop pin 74 with a stationary stop pin 82 fixed to and projecting inwardly from the lead screw mounting section 26a at a location readily spaced from the longitudinal axis of the lead screw 26 and along the path of the movable stop pin 74 (see FIG. 4).

A typical sequence of operations will now be described in order to facilitate a more thorough understanding of the invention.

When the potentiometer 10 is incorporated into an operating environment of system and input is applied to the control shaft 40, either automatically or manually, rotation of the control section 40b will cause a corresponding rotation of the crosshead 50 and of the drive fingers 54, 56. The drive fingers 54, 56 due to their coupling with the follower nut 32, will cause the same to rotate about and traverse along the lead screw section 26b thereby imparting a corresponding motion to the follower assembly 30 and the wiper 38. The segment of the contact section 38a underlying the resistance wire 22 will move in a helical path corresponding to the pitch of the lead screw 26 and to the comparable pitch of the groove 20 thereby providing a stepless output which will be a function of the relative position of the contact section 38a along the resistance wire 22. The contact pressure of the wiper or brush 38 may be established to provide relatively low frictional contact with the resistance wire 22 yet achieving the necessary electrical tapoff thereby assuring long life and relatively low wear. Further, since the wiper or brush 38 follows the exact helical path of the resistance wire 22 there will be a minimum sliding or helical error between the contact and wire. By appropriate selection of materials and control in manufacturing tolerances, a high order of linearity may be attained for the potentiometer and optimum mechanical conditions may be established for the product.

Reference will now be made to FIG. 6 which shows a modification of the high resolution potentiometer, particularly in the construction of the collector means which electrically and rotatably connects the movable wiper or brush to the resistance wire for providing the stepless output. Since the construction of this potentiometer is substantially identical to that previously described, corresponding parts will be designated by the same reference numeral as a part of a "100" series and the detailed description will be limited only to the construction of the collector means which may be employed in lieu of the collector cylinder 58 and the brushes 60. Specifically, an annular collector ring 158 is mounted on the end face of the wire form 118 remote from the mounting plate 114. The collector ring, which is in the form of a flat annulus, is disposed concentrically of the lead screw 126 and electrically contacted by the movable contacts or brushes 160 which are mounted on the cross head 150 by an appropriate insulating block 161. The insulating block 161 is secured to the cross head 150 by appropriate mounting screws or bolts 163, while the brushes 160 are connected to a terminal plate 165 which is riveted or otherwise secured to the insulating block 161. The electrical connection from the brushes 160 via the terminal plate 165 to the wiper mounting arm 136 and to the brush or wiper (not shown but comparable to the brush or wiper 138) is completed by the provision of a jumper wire 167 which is electrically connected at one end to the terminal plate 165 and at the other end to the wiper mounting arm 136. The jumper wire 167 is flexible and is of sufficient length such as not to interfere with the movement of the follower nut 132 along the lead screw 126 and yet provides the necessary electrical connection between the movable follower assembly and the stationary collector ring 158. In this embodiment, it will be appreciated that the brushes 160 traverse the same annular contact paths on the collector ring 158 and may be initially constructed to be of a relatively narrow width comparable to the spacing be-

tween the brushes. Obviously, this represents a saving as compared to the use of the relatively long cylindrical collector ring 58 and results in manufacturing economies, particularly when it is recalled that the collector ring is usually fabricated or plated of a precious metal.

A latitude of modification, change and substitution is intended in the foregoing disclosure and in some instances some features of the invention will be employed without a corresponding use of other features. Accordingly it is appropriate that the appended claims be construed broadly and in a manner consistent with the spirit and scope of the invention herein.

What we claim is:

1. An infinite resolution potentiometer comprising a mounting plate, a cylindrical wire form of an insulating material projecting from said mounting plate and having an outer surface formed with a continuous helical groove, a helically wound resistance wire mounted within said groove, a stationary lead screw secured to said mounting plate and projecting within and along the longitudinal axis of said wire form, a follower in threaded engagement with said lead screw, a wiper arranged contiguous to said outer surface of said wire form and having a contact section underlying and engaging said resistance wire, means mounting said wiper on follower for movement along a helical adjustment path coextensive with said resistance wire, and control means operatively connected to said follower for rotating said follower on said lead screw to move said wiper along said adjustment path.
2. An infinite resolution potentiometer comprising a mounting plate, a cylindrical wire form of an insulating material projecting from said mounting plate and having an outer surface formed with a continuous helical groove, a helically wound resistance wire mounted within said groove, a stationary hollow lead screw secured to said mounting plate and projecting within and along the longitudinal axis of said wire form, a follower in threaded engagement with said lead screw, a wiper arranged contiguous to said outer surface of said wire form and having a contact section underlying and engaging said resistance wire, means mounting said wiper on follower for movement along a helical adjustment path coextensive with said resistance wire, and control means operatively connected to said follower for rotating said follower on said lead screw to move said wiper along said adjustment path,
3. An infinite resolution potentiometer comprising a mounting plate, a cylindrical wire form of an insulating material projecting from said mounting plate and having an outer surface formed with a continuous helical groove, a helically wound resistance wire mounted within said groove, a stationary hollow lead screw secured to said mounting plate and projecting within and along the longitudinal axis of said wire form, a follower in threaded engagement with said lead screw, a wiper arranged contiguous to said outer surface of said wire form and having a contact section underlying and engaging said resistance wire, means mounting said wiper on follower for movement along a helical adjustment path coextensive with said resistance wire, control means operatively connected to said follower for rotating said follower on said lead screw to move said wiper along said adjustment path, and collector means including a control shaft journaled in said mounting plate and extending coaxially of and through said lead screw and means coupling said control shaft to said follower.
4. An infinite resolution potentiometer according to claim 3 wherein said collector means includes a collector cylinder coaxially of and within said wire form, and brush means in rotatable contact with said collector cylinder and electrically connected to said wiper.
5. An infinite resolution potentiometer according to claim 3 wherein said collector means includes an annular collector ring extending transversely of said longitudinal

axis and mounted on said wire form, and brush means in rotatable contact with said collector ring and electrically connected to said wiper.

6. An infinite resolution potentiometer comprising a mounting plate, a cylindrical wire form of an insulating material projecting from said mounting plate and having an outer surface formed with a continuous helical groove, a helically wound resistance wire mounted within said groove, a stationary hollow lead screw secured to said mounting plate and projecting within and along the longitudinal axis of said wire form, a follower in threaded engagement with said lead screw, a wiper arranged contiguous to said outer surface of said wire form and having a contact section underlying and engaging said resistance wire, means mounting said wiper on follower for movement along a helical adjustment path coextensive with said resistance wires, control means operatively connected to said follower for rotating said follower on said lead screw to move said wiper along said adjustment path, said control means including a control shaft journaled in said mounting plate and extending coaxially of and through said lead screw and means coupling said control shaft to said follower, collector means electrically and rotatably connected to said wiper for providing a tapoff connection thereto, and terminal means electrically connected to the opposite ends of said resistance wire.

7. An infinite resolution potentiometer according to claim 6 wherein said collector means includes a collector cylinder coaxially of and within said wire form, and brush means in rotatable contact with said collector cylinder and electrically connected to said wiper.

8. An infinite resolution potentiometer according to claim 6 wherein said collector means includes an annular collector ring extending transversely of said longitudinal axis and mounted on said wire form, and brush means in rotatable contact with said collector ring and electrically connected to said wiper.

9. In an infinite resolution potentiometer, mounting means including a wire form having a helical groove, a resistance wire mounted in said groove, a stationary lead screw supported on said mounting means and extending axially of said resistance wire, said lead screw having a pitch substantially corresponding to the pitch of said helical groove, a follower engaging said lead screw and movable therealong in response to being rotated, a brush underlying said resistance wire and operatively connected to said follower for movement therewith and making contact with successive portions of said resistance wire, and

control means operatively connected to said follower for rotating said follower.

10. An infinite resolution potentiometer comprising mounting means including a wire form having a helical groove, a resistance wire mounted in said groove, a stationary lead screw supported on said mounting means and extending axially of said resistance wire, said lead screw having a pitch substantially corresponding to the pitch of said helical groove, a follower engaging said lead screw and movable therealong in response to being rotated, a brush underlying said resistance wire and operatively connected to said follower for movement therewith and making contact with successive portions of said resistance wire, control means operatively connected to said follower for rotating said follower, collector means electrically connected to said brush and including a stationary terminal providing a stepless output from said brush, and terminal means electrically connected to the opposite ends of said resistance wire respectively.

11. An infinite resolution potentiometer comprising mounting means including a wire form having a helical groove, a resistance wire mounted in said groove, a stationary lead screw supported on said mounting means and extending axially of said resistance wire, said lead screw having a pitch substantially corresponding to the pitch of said helical groove, a follower engaging said lead screw and movable therealong in response to being rotated, a brush underlying said resistance wire and operatively connected to said follower for movement therewith and making contact with successive portions of said resistance wire, control means operatively connected to said follower, said control means including a control shaft journaled on said mounting means and extending coaxially of and through said lead screw and drive means carried on said control shaft and slidably coupled to said follower for rotating said follower, collector means electrically connected to said brush and including a stationary terminal providing a stepless output from said brush, and terminal means electrically connected to the opposite ends of said resistance wire respectively.
